CLAIM

The ornamental design for replacement caulking tip, as shown and described.

DESCRIPTION

FIG. 1 is an isometric view of a replacement caulking tip showing my new design;
 FIG. 2 is a front elevational view thereof;
 FIG. 3 is a rear elevational view thereof;
 FIG. 4 is a left side elevational view thereof;
 FIG. 5 is a right elevational view thereof;
 FIG. 6 is a top plan view thereof;
 FIG. 7 is a bottom plan view thereof; and,
 FIG. 8 is an isometric view of the replacement caulking tip in an environment of use adjacent to a caulking device. The broken line depiction of the caulking device and nozzle is provided for purposes of environment and forms no part of the claimed design.
